WRITING DEVICE

Martin Berliner and Alfred Matlas,
New York, N. Y.

Application July 21, 1943, Serial No. 495,562

5 Claims.

(Cl. 35—66)

This invention relates to writing devices or writing pads for permanent use, and more particularly to a writing device of the aforesaid type which is susceptible of being operated to render inscriptions on its surface readily indiscernible or to efface such inscriptions.

It is one of the objects of this invention to provide a very efficient and sturdy writing device of the aforesaid nature, which is very simple and inexpensive in construction, may be easily manipulated and is light in weight since it is practically devoid of any metallic parts.

It is a further object of this invention to provide a device having means for guiding a movable portion of the device and for causing almost instantaneous disappearance of inscriptions on the surface of the writing device.

Still another object of the present invention is to provide a writing pad whose frame is made from an envelope into which a writing unit may be slidably inserted and held in position therewith.

Yet, a further object of the present invention is to provide means in the form of a parting strip which assures reliable operation and which interconnects said slidable writing unit with the envelope, said strip being fastened to the inside of the envelope and being hidden from outside view.

It is another object of this invention to provide a writing pad or device of the aforesaid nature which is substantially made of paper and allows ready assembly of its parts of which it consists.

These and other objects and advantages of the invention will appear from the following disclosure thereof together with the attached drawing which illustrates a certain form of embodiment thereof. This form is shown for the purpose of illustrating the invention since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the drawing:

Fig. 1 is a front elevation of the writing device made in accordance with the invention, shown in operative position.

Fig. 2 is a similar view to Fig. 1, the device being in partially operating position.

Fig. 3 is a rear view of Fig. 2.

Fig. 4 is a perspective view of the frame of the

device, the top portion being slightly compressed to demonstrate the top opening and location of securing for the parting strip of the device.

Fig. 5 is a front elevation of the writing unit in the stage of being assembled.

Fig. 6 is a perspective view of the parting strip.

Fig. 7 is a fragmentary sectional view, taken along lines 7—7 of Fig. 5.

Fig. 8 is a sectional view, taken along lines 8—8 of Fig. 1.

Fig. 9 is a sectional view, taken along lines 9—9 of Fig. 1.

In the embodiment of the invention shown in Fig. 1, there is disclosed a writing device 15 provided with a frame 16 in the form of an envelope having front wall 17 with cut-out or window 18 and rear wall 19. Front wall 17 has two flaps 20 and 21 which are turned over and secured to rear wall 19, as clearly indicated in Fig. 3. Envelope or frame 16 is further provided with upper cut-outs 22 at the front wall 17 and rear wall 19 to make the writing board or unit 23 accessible to the fingers of the hand of the operator. Envelope 16 may be made of canvas, leather, paper, cardboard or any other suitable material.

Writing unit or board proper 23 consists of a plurality of layers about to be described herein-after.

The lowermost or base layer of the pad consists of a base plate preferably of cardboard 24 to which is fastened by any attaching means, such as wire staples 25, the top layer or cover 26 in form of a transparent sheet 26. Between base layer 24 and top layer 26, there is slidably received assembled intermediate layers 29 consisting of black wax covered support 30, tissue or other known translucent sheet 31 and parting strip 32.

Tissue sheet 31 which is translucent loosely 40 overlies support or holder 30 and is provided with upper and lower flaps 31a (Fig. 7) by which tissue sheet 31 is held in position on the wax covered support. To this end, flaps 31a are loosely bent over the rear side of support 30. Between the 45 surface of black wax covered support 30 and translucent tissue sheet 31, there is positioned parting strip 32 which in turn is provided with end portions or extensions 33, 34 bent over at 35 and 36, respectively (Fig. 6).

The thus assembled intermediate layers 29 are slidably arranged with a certain play between base layer 24 and transparent top layer 26 (Fig. 5) resulting in the structure of the writing board proper or unit 23. Writing board 23 may then 55 be slidably mounted in envelope or frame 16 by in-

sertion of said board into its upper opening 16a, extensions 33 and 34, which were prior to the insertion bent over the rear side of the base layer 24, being thereafter attached with their surfaces 31, 38 to the inside of the envelope at its rear wall 39 and at locations 40 and 41 thereof which are preferably provided with respective adhesive layers. Thus, the writing board proper 23 may be easily retained and held in position within envelope or frame 16, but is permitted to slide therein, since the width of the board 23 corresponds approximately to the inside width of the envelope. The writing or top surface 26 of transparent material is exposed to view at window 19 of frame 16, as clearly indicated in Fig. 1.

The function of the writing device 15 is well known in the art. As can be seen in Fig. 1, any indicia or inscriptions on the top surface 26 of the writing pad may be produced by pressing the transparent top sheet 26 against the translucent tissue sheet 31, which in turn is then pressed against the wax covered holder 30. Parting strip 32 will efface the indicia or inscription due to a sliding movement of the writing board 23 relatively to the strip 32 which is stationary and fixedly attached to frame 16 and thereby lifts the tissue sheet 31 from the black wax covered surface 30.

It is to be noted that the length of the intermediate layers 29 is somewhat shorter than the distance between the upper and lower pairs of wire staples 25, the latter attaching the transparent top layer or cover 26 to base plate 24. Thus, the coefficient of expansion of the tissue layer or sheet 31 and that of the wax covered holder or support 30 are taken into consideration, since said coefficients are varying due to humidity, temperature and other climatic influences. Consequently, the workability of the writing device is improved and a smooth operation thereof is assured. The upper and lower pairs of wire staples 25 serve further the purpose of forming upper and lower stops for the assembled intermediate layers 29 which are capable of extending somewhat in lengthwise direction.

As seen in Figs. 5 and 7, transparent top or cover plate 26 and base layer 24 are also firmly held together by top and bottom edgings or binding strips 27 which prevent unraveling of the flexible layers forming the writing board or unit 23. Said binding strips or edgings 27 have further the purpose of facilitating guiding of the writing unit 23 within and along the inner lateral edges of the envelope.

While there has been shown and described and pointed out the fundamental novel features of the invention as applied to the above embodiment, it will be understood that various omissions, substitutions and changes in the form and details of the device illustrated and the operation thereof may be made by those skilled in the art without departing from the spirit of the invention.

Having thus described the invention what is claimed as new and desired to be secured by Letters Patent, is:

1. A writing device of the character described comprising an elongated envelope having an open end, a front wall and a rear wall; said front wall being provided with a cut-out forming a window, a writing unit arranged to slide through said open end of said envelope, the surface of said unit being exposed to view at said window, a paper strip interconnecting said writing unit with said envelope, said writing unit comprising a base

plate and a transparent cover, staples connecting said cover to said base plate at their respective upper and lower edges, and intermediate layers loosely interposed between and retained by said base plate and said cover and comprising a holder, a tissue sheet extending above and fixed to said holder and a wax coating on said holder positioned underneath said tissue sheet, said paper strip transversely extending below said tissue sheet and above said wax coating and terminating in lateral extensions bent over the rear face of said base plate, and adhesive means fixedly connecting said lateral extensions to the inner face of the rear wall of said envelope, whereby indicia caused by compressing said tissue sheet against said wax coating may be effaced upon movement of said writing unit within said envelope and past said paper strip.

2. A writing device of the character described comprising an elongated flexible envelope having an open end, the front wall of said envelope being provided with a cut-out forming a window, a writing unit arranged to slide through said open end and exposed with its surface to view at said window, a strip interconnecting said writing unit with said envelope and positioned adjacent said open end, said writing unit comprising a base plate and a transparent cover, means connecting said cover with said base plate at their respective upper and lower edges, and a plurality of layers loosely interposed between and retained by said base plate and said cover and displaceable within the confines of said connecting means; said layers comprising a support, a tissue sheet overlying said support and fixed thereto, and a wax coating on said support and positioned below said tissue sheet; said strip transversely extending below said tissue sheet and above said wax coating and being provided with lateral extensions bent over to extend toward the rear face of said base plate, and adhesive means fixedly connecting said lateral extensions to the rear wall at the inside of said envelope, said bent over extensions providing lateral guides for said writing unit when sliding within said envelope, whereby indicia caused by pressing said cover against said tissue sheet and said wax coating may be effaced upon sliding movement of said writing unit within said envelope and past said strip.

3. A writing device of the character described comprising an elongated envelope made of paper and having an open end, the front wall of said envelope being provided with a cut-out forming a window, a writing unit arranged to slide through said open end and exposed with its surface to view at said window, a paper strip interconnecting said writing unit with said envelope and positioned adjacent said open end, said writing unit comprising a base plate and a transparent cover, wire staples connecting said cover to said base plate at their respective upper and lower edges, a plurality of layers loosely interposed between said base plate and said cover and displaceable between said upper and lower edges and within the confines of said wire staples, said layers comprising a support, a tissue sheet overlying said support and held thereon, and a wax coating on said support, said paper strip being positioned below said tissue sheet and above said wax coating and being provided with lateral extensions bent over the rear face of said base plate, adhesive means fixedly connecting said lateral extensions to the rear wall at the inside of said envelope, whereby indicia caused

by pressing said cover against said tissue sheet and said wax coating may be effaced upon movement of said writing unit within said envelope and past said strip, and binding strips, respectively, positioned at said upper and lower edges and reinforcing said writing unit, said binding strips being adapted to facilitate guiding of said writing unit lengthwise of said envelope.

4. A writing device of the character described comprising a flexible envelope provided with a window, a writing unit having a plurality of successive layers and slidably arranged in said envelope, said successive layers comprising two outer layers and layers positioned intermediate said outer layers and including a thin sheet of translucent material arranged immediately below the uppermost layer of said unit, said uppermost layer being transparent, top edgings and bottom edgings, respectively, provided at the outer layers and binding the latter together, said writing unit being exposed to view with a portion thereof at said window and being adapted to produce an indicia upon compressing said thin translucent sheet upon the layers therebelow, a strip extending transversely of said writing unit and disposed below said thin translucent sheet, and lateral extensions provided at said strip and projecting beyond said unit for attachment to a wall of said envelope within the interior of the

latter whereby said thin translucent sheet may be separated from said layers therebelow by said strip upon sliding movement of said unit within said envelope.

5. A writing device of the character described comprising a flexible envelope provided with a window, a writing unit having a plurality of successive layers and slidably arranged in said envelope, said successive layers comprising two outer layers and layers positioned intermediate said outer layers and including a thin sheet of translucent material arranged immediately below the uppermost layer of said unit, said uppermost layer being transparent, said writing unit being exposed to view with a portion thereof at said window and being adapted to produce an indicia upon compressing said thin translucent sheet upon the layers therebelow, a strip extending transversely of said writing unit and disposed below said thin translucent sheet, and lateral extensions provided at said strip and projecting beyond said unit for attachment to a wall of said envelope within the interior of the latter whereby said thin translucent sheet may be separated from said layers therebelow by said strip upon sliding movement of said unit within said envelope.
